UNITED STATES PATENT OFFICE.

WILLIAM F. PAGEL, OF SYCAMORE, ILLINOIS.

TORCH.

1,343,403.

Specification of Letters Patent. Patented June 15, 1920.

Application filed July 26, 1919. Serial No. 313,547.

To all whom it may concern:

Be it known that I, WILLIAM F. PAGEL, a citizen of the United States, residing at Sycamore, in the county of Dekalb, and State of Illinois, have invented a certain new and useful Improvement in Torches, of which the following is a full, clear, concise, and exact description, reference being had to the accompanying drawings, forming a part of this specification.

My invention relates to improvements in blow pipe torches, particularly that class of torches known as plumber's blow pipe torches.

The fuel for such torches has heretofore been limited to gasolene and particularly gasolene of good quality, viz., easily vaporized. It is well known that the grade of available gasolene is gradually dropping down and it is practically impossible to successfully operate the ordinary plumber's blow pipe torch with this lower grade gasolene, due mainly to the impossibility of applying sufficient heat to the fuel as it approaches the outlet orifice to cause it to properly gasify upon escape into the flame. Another difficulty which is aggravated by the low grade fuel now available is that as commonly constructed the adjusting valve of the torch becomes so highly heated as to deposit carbon upon the valve surface and in shutting off such a valve the parts are liable to be distorted to such an extent as to preclude proper adjustment of the flame or the proper closing of the shut off.

Still another detrimental feature of the plumber's blow pipe torches now commonly used is that as commonly constructed the air pump, for placing the liquid fuel under pressure for lifting it to the burner, is connected to the casing of the torch by a connection which permits more or less gasolene to leak, this is a source of considerable annoyance and waste and it is relatively expensive to produce.

In the torch of my invention I provide simple means for applying sufficient heat to the fuel, as it approaches the burner orifice, so that I am not only enabled to successfully make use of the lower grades of gasolene, but I am enabled to make successful use of kerosene as a fuel for such torches, which, so far as I am informed, has not been successfully attained before. I am also enabled to protect the burner from becoming de-

stroyed, as I supply a shutoff valve at such a distance from the orifice that the deposit of carbon is prevented, and I make use of the adjustable valve at the orifice merely for the purpose of adjusting the flame, not for entirely shutting off the flow of fuel when the torch is not in use.

Even if carbon should be deposited upon and about the shut off valve this would be no serious detriment to the device as the shut off valve is not used for adjusting the flow of fuel to the escape orifice for regulating the flame, but merely to turn on or shut off the fuel supply.

My invention also includes the feature of attaining a substantially perfect mixture of the fuel and air and an air admission means in the flame tube which works in combination with my novel preheating means for the attainment of the result desired.

Furthermore, I have provided a simple, compact connection for the air pump which is easily manufactured and which eliminates the possibility of leakage of the fuel at this point.

The several ideas embraced in my invention and embodied in my improved torch all cooperate to provide a blow pipe torch which is more durable, particularly in its delicate parts, which successfully uses low grade gasolene or kerosene for fuel and which can be readily manufactured by the use of the usual shop equipment.

My invention will be more readily understood by reference to said accompanying drawings in which:

Figure 1 is a side elevation, partly in vertical section, of a torch made in accordance with my invention;

Fig. 2 is a fragmentary top plan view of the burner tube and feed nozzle;

Fig. 3 is a detail vertical section on the line 3-3 of Fig. 1.

Fig. 4 is a fragmentary detail horizontal section on the line 4-4 of Fig. 1.

Fig. 5 is a view in elevation of the container shown in Fig. 1.

Fig. 6 is a fragmentary vertical section similar to Fig. 1 showing a slight modification of the invention; and

Fig. 7 is a view in side elevation of the woven wire container shown in Fig. 6.

In said drawings 1, is a reservoir for the liquid fuel, provided at its lower end with a filling plug 2. Upon one side of the reser-

voir is mounted a vertical standpipe 3 through which the liquid fuel is fed to the burner which is designated generally by 4 and is mounted upon the upper end of the standpipe.

The burner comprises a cylindrical flame tube 6, provided with an interiorly threaded nozzle 7 at the middle of its lower side and by which the flame tube is mounted upon the upper end of the standpipe 3. Within the connection 7, I provide a chamber 8, the lower wall 9, of the flame tube above the chamber being formed into a rounded baffle or projection extending within the tube at its lower side and providing a hollow baffle against which the flame which is produced within the tube 6, is adapted to impinge in its passage through the tube. The projecting wall of the hollow baffle is relatively thin and is adapted to transmit a relatively large quantity of heat to the fuel within the chamber 8.

At the receiving end of the flame tube it terminates in a mixing tube 10 which is concentric with the flame tube and in axial alinement therewith. The mixing tube is relatively short and terminates at its outer end in an outwardly flared or coned mouth 11. Its inner end is joined to the adjacent end of the flame tube by an end wall 12.

Opposite to the flared end of the mixing tube, I arrange a feed nozzle 13 which is in axial alinement with the mixing tube and is provided with a delivery orifice 14 of relatively small diameter through which the generated gas is adapted to be forced in a fine stream which is projected axially into the open end or mouth of the mixing tube. The delivery nozzle is flared or coned inwardly from the orifice 14 and I provide a valve stem 14' in axial alinement with the orifice and provided with a coned or tapered end adapted to fit within the tapered nozzle 13 and control or adjust the escape of the gas through the orifice. For adjusting the valve longitudinally from and toward the orifice, I provide a threaded opening 16 in said nozzle and the valve stem is correspondingly threaded. The rear end of the stem 14 extends through a suitable stuffing box 18 and is squared at its extreme end for the application of a suitable wrench or handle for adjusting the stem in the threaded opening.

For delivering the gas from the chamber 8 to the delivery nozzle a feed passage 19 is provided, extending rearwardly from the chamber 8 in the lower wall of the flame tube and terminating in an enlarged opening 20 threaded to receive a forward extension 21 of the nozzle casting. The feed passage is continued in the extension 21 and is joined to the nozzle proper by a vertical passage 22. For cutting off the feed a needle shutoff valve 23 is provided arranged in alinement with the feed passage 19 and hav-

ing a coned tip 24 adapted to be closed upon a valve seat 25 at the rear end of the feed passage 19. The valve stem 23 is threaded and is mounted in a threaded opening 26 provided in the nozzle casting so that it can be opened and closed by rotation therein. The stem extends out through a suitable stuffing box 27 and carries on its outer end a hand wheel 28.

The valve 14' is used merely for adjusting the area of the delivery orifice, while the valve 23 is used for controlling the flow of the fuel to the nozzle. The delivery orifice remains open at all times and after the torch has been in use and has become heated and it is desired that it be shut down, the flow of fuel is stopped by closing the valve 23 against the seat 25. As the gas flowing from the generator to the orifice 14 is quite hot any gas which is contained in the nozzle on the vertical feed passage 22 when the valve 23 is closed escapes through the orifice 14 without depositing any carbon, and even if carbon should be deposited about the valve 23, which is not likely, this could not affect the operation of the torch as valve 23 can always be operated to shut off the flow of gas completely and is not used for any delicate adjustment of the flow of gas.

The means which I employ for effecting the generation of gas comprises the hollow baffle 9 and the upper end of the chamber 8 and means for causing the liquid fuel to be carried into contact with the under surface of the baffle or at least close enough to it to be gasified. This means consists of a hollow thimble-like member 29 which is freely open at its upper end and slightly coned at its lower end 30. Its lower end is adapted to be seated in the upper end of the standpipe 3 and is partly closed by an inner circumferential flange 31. The center of the lower end is open to permit the fuel oil to rise through this member.

For the purpose of causing the fuel oil to rise into contact with the under surface of the baffle 9 I fill the member 29 with mineral wool, asbestos or some similar fibrous material 32, adapted to withstand a considerable degree of heat. The mass of the filling 32 is sufficient to fill the member 29 and form a projecting portion above the upper end thereof sufficient so that when the torch parts are assembled the projecting mass of the filling material will be pressed into firm contact with the baffle 9 and the member 29 will be seated tightly upon the upper end of the standpipe 3. The member 29 is made of such a length that its upper edge does not contact with the baffle but leaves a space at its upper end through which the generated gas can escape after being formed by the heat transmitted through the baffle 9. The seating of the member 29 upon the upper end of the standpipe 3 closes off the stand-

pipe except for the opening through the member 29 and causes all of the liquid to rise through the member 29 substantially into contact with the baffle 9 to be gasified 5 in its passage to the nozzle. The gas which is thus produced is hot and dry even when kerosene is used for fuel.

Such torches are usually provided with a pan such as 33 for the burning of some of the fuel in lighting the torch to heat the burner tube and the nozzle. I make the pan 33 separate from the flame tube and mount it on the standpipe 3 in a very simple manner which not only holds the pan in proper 15 position, but makes the pan liquid tight at its bottom where the pipe 3 projects through same.

For this purpose, I preferably press the pan out of sheet metal. The pan has a bottom wall 34 and a side wall 35. I make a hole 36 in the bottom wall through which the pipe 3 projects and I provide a thimble 37 sliding freely on the upper end of the pipe 3 and long enough to reach from the 25 bottom of the pan to the lower end of the nozzle 7 on the flame tube. For tightly binding the pan 33 and the thimble 37 in position, I provide a nut 38 threaded upon the upper end of the pipe 3 and adapted to 30 be screw hard up against the lower side of the pan. In assembling the device the flame tube is screwed down upon the upper end of the pipe 3 to form a pressure tight connection therewith and then the nut 38 is secured up to hold the pan and thimble tightly 35 against the lower end of the nozzle 7. By this means I am enabled to seat the pan 33 beneath the flame tube and to make a tight joint between the lower end of the thimble 37 40 and the bottom of the pan.

The pump 5 consists of a thin walled pump cylinder 39, in which is arranged a piston 40 secured on the lower end of an operating rod 41. The piston 40 comprises 45 a leather cup 42 and head 43 threaded on to the lower end of the rod and clamping the leather cup against a shoulder 44 on the rod. The lower end of the cylinder 39 is externally threaded and is mounted in a 50 threaded opening 45 provided in a connection member 46. The lower end of the cylinder seats firmly upon the bottom of the opening 45 and makes a pressure tight joint at this point. The connection 46 is provided 55 with a horizontal passage 47 which gives access to the receiver 1, and the outer end of the passage terminates in a valve chamber 48 below the pump cylinder. A port 49 connects the chamber 48 with the pump 60 cylinder, opening through the bottom of the opening 45 in which the pump cylinder is mounted.

For controlling this port 49 I provide a valve 50 within the chamber 48 having a 65 head 51 at its upper end adapted to close

upwardly against a seat 52. The valve has a stem 53 guided at its lower end in a guide opening formed in a head 54 by which I close the lower end of the chamber 48. The valve is normally held up against the seat 70 by a compression spring 55 which surrounds the valve stem 53 and is compressed between the valve head 5 and the closure 54. The valve thus constructed is a check valve, which permits air to enter the reservoir 75 from the pump cylinder but prevents the fuel oil rising into the pump cylinder or obtaining access to the joint between the cylinder and the connection.

This form of mounting of the pump and 80 its connection with the reservoir is very substantial and strong, it is very simple to manufacture, and it is more durable than such connections have been heretofore.

In operating, the reservoir having been 85 filled nearly full of the fuel oil, the valve 23 is closed and the pump operated to produce a pressure within the reservoir. The valve 23 is opened to let the liquid fuel rise up to the nozzle and drip into the pan 33, 90 where it accumulates and is burned to heat up the torch. The valve 23, meanwhile is closed again. As soon as the flame tube becomes heated sufficiently, the valve 23 is again opened and the pressure forces the 95 fuel out of the orifice 14 through the mixing tube and through the flame tube, the fuel in its passage through the chamber 8 and the feed passage 19, becoming heated sufficiently to expand into gas as it is released from the orifice. 100

This expanding stream of fuel enters the coned inlet 11 of the mixing tube 10 and draws sufficient air with it to produce a flame once it has been lighted. The flame 105 is projected through the flame tube.

Once a flame has been produced it impinges against the hollow baffle which soon transmits sufficient heat to the fuel held in contact therewith by the fibrous material 32 110 as to completely gasify the fuel so that when the torch is in full operation only dry hot gas passes through the feed passages 19 and 22 to the orifice 14.

In addition to the air mixing with the 115 fuel in the mixing tube it is desirable to provide another means for feeding air to the flame in the flame tube. For this purpose I provide a narrow elongated slot 56 extending substantially from end to end of the flame tube 6 and arranged in the upper side thereof. This slot not only provides means for the addition of air at this point, but the air in entering at the upper side of the tube tends to force the flame down upon the baffle 9 and thereby assists in heating same. 120

In Figs. 6 and 7 I have illustrated a slightly modified form of container for the mineral wool or such like material in the chamber 8. In this form the container 57 instead of being in the form of a tube is 125 130

made of woven wire in the form of a basket fitting loosely within the chamber and adapted to hold the mineral wool and prevent it dropping down into the open end of the standpipe 3. The capillary action within the body of the mass of fibrous material insures the contact of the liquid with the top upper wall of the chamber and the consequent vaporization of the fuel.

10 As many modifications of my invention will readily suggest themselves to one skilled in the art, I do not limit or confine my invention to the specific structures herein shown and described.

15 I claim:

1. In a blow pipe torch, an elongated cylindrical flame tube, the entrance end thereof being contracted, a fuel feed nozzle in alignment with said tube and adapted to direct fuel through said contracted end to form a flame within the tube, a hollow baffle projecting into one side of the tube substantially midway between its ends and against which the flame is adapted to impinge, and means 20 for forcing liquid fuel through said hollow baffle to be vaporized as it passes to said nozzle.

2. In a blow pipe torch, a flame tube having a contracted entrance end, a fuel feed nozzle having an orifice in alignment with said tube and adapted to direct fuel through said contracted end to form a flame within the tube, a hollow baffle projecting into one side of the tube in the path of the flame, 25 said flame tube having a longitudinal air admission slot in its wall opposite to said baffle, and means for forcing fuel through said hollow baffle and nozzle to the orifice.

3. In a blow pipe torch, a flame tube, a fuel feed nozzle having a feed orifice in alignment with said tube, an air mixing tube of relatively small diameter, also in alignment with the flame tube, and having a flared end into which said nozzle is adapted to project the fuel, said inlet constituting a contracted entrance to said flame tube, a thin walled hollow baffle projecting into one side of the tube between its ends and against which the flame is adapted to impinge, and 45 means for forcing fuel oil into contact with

said baffle to be vaporized and for directing the gas formed to said nozzle.

4. In a blow pipe torch of the kind described, a flame tube, an air mixing tube smaller in diameter than the flame tube in 55 alignment therewith, the receiving end of the air mixing tube flared outwardly to form a coned end, a fuel feed nozzle adapted to project fluid fuel into said flared end of the air mixing tube and form a flame in said flame tube, the flame tube having air admission means at one side between its ends, a hollow baffle projecting into the flame tube opposite to said air admission means, said baffle being thin walled and hollow, and means for causing liquid fuel to contact with the inner surface of the thin wall of the baffle to be gasified and to be delivered to said nozzle.

5. In a torch of the kind described, a flame tube, a fuel feed nozzle adapted to project fuel into one end of said flame tube to form a flame, a thin walled hollow baffle projecting into said flame tube from one side, a fuel heating chamber within said baffle, a tubular container for mineral wool within said chamber, a fuel passage entering the lower part of the chamber, the lower end of said container entering the mouth of said feed passage, mineral wool or the like in said container and held thereby against said thin walled baffle, the upper end of the container spaced from the baffle wall, and a passage leading from said chamber to said nozzle.

6. In a burner of the kind described, a flame tube a fuel feed nozzle having an orifice in alignment with said tube and adapted to project a flame through said tube, said nozzle being coned and provided with a coned needle valve for adjusting said orifice, 80 said flame tube having a fuel heating passage in its side wall through which fluid fuel is forced to said nozzle and a shut-off valve at a distance below said nozzle for shutting off the flow of liquid fuel to said nozzle.

In witness whereof I hereunto subscribe my name this 22nd day of July, A. D. 1919.

WILLIAM F. PAGEL.
